12 Claims. (Cl. 312—27)

This invention relates to means for enabling articles such as typewriters, sewing machines, or other apparatus to be stowed and presented for access.

5 The invention has for an object the provision of means for the above purpose, which are operable with little effort on the part of the user, whilst occupying small space, whereby it may be embodied in an article of furniture.

10 Another object of the invention is to incorporate in such means the important feature of means for preventing its movement from one position to another, whilst the article, e. g. typewriter, itself is in such a position or condition that it 15

15 might suffer damage through being moved.

A further object of the invention is to provide means for the purpose stated, constructed as a unitary structure, whereby it comprises a complete device easily fittable in an article of furniture, such as a pedestal of an office desk. In a primary application of the invention the means are adapted for mounting a typewriter so as to enable it to be stowed in the space normally occupied in a desk pedestal by, say, two upper drawers, 20 and to be readily moved from that accommodation to one outside the pedestal and at a reasonable height and rigidly supported and equally capable of being returned to its stowed position.

In the accompanying drawings an embodiment 30 of the means according to the present invention is illustrated. The device shown is for use in stowing and presenting for access a typewriter. It will be appreciated, however, that the invention is applicable to other articles, machines, instruments or the like, which are required sometimes to be stowed and sometimes to be exposed and raised for access, e. g. gramophone mechanism, sewing machines, or maybe wash basins which form part of ships cabin or like accommodation. 35 Normally the article to be stowed will be rested on a movable platform which for convenience will hereinafter be called the support.

In the drawings:—

Figure 1 is a cross section through a desk compartment forming the housing for a typewriter when stowed showing the device installed.

Figure 2 is an enlarged view showing the details of the spring adjustment means.

Figure 3 is an enlarged fragmentary view showing the locking means for retaining the tray in its extended and raised positions, and a feeler safety device.

Figure 4 is a plan view of Figure 3.

Figure 5 shows in detail the slideway in which 55 the support is movable.

Figure 6 is an enlarged fragmentary view showing means for preventing premature view and sliding of the tray during lowering from the raised position.

Figure 7 is a diagrammatic perspective view of 5 the device.

In Figure 1 there is shown a compartment 10 of sufficient dimensions to accommodate a typewriter generally indicated in broken lines at 11. The machine is carried on a tray 12, which is slidably carried between guides 13 and locked therein by a catch not shown, which is releasable to allow withdrawal of the tray for cleaning and like purposes. In normal operation of the means the tray is securely locked to the guides 13. The tray and 15 guides form a support for the typewriter, which support is carried between the two inwardly opposed U section channels 14 forming guides, there being interposed between the guides 13 and channels 14 ball races comprising a cage 15 with balls 20 16, as shown in Figure 5. By this arrangement the comparatively effortless and smooth inward and outward movement of the support is obtained. By using balls 16 of sufficiently small diameter excessive movement of the cages 15 is prevented. 25 Stops are provided at each end of the channels 14 to retain the cages, and the latter are connected to move together by a bar 15A.

To prevent any rise of the platform before its 30 complete withdrawal, or outward horizontal sliding has been accomplished, there are attached to the inside of the guide 13, i. e. to the typewriter support, downwardly extending legs 18 terminating in rollers 19, which rollers 19 engage the top flange of a further set of fixed guide 35 rails 20. The guides form part of the framework of the device and are fixed low down to the walls of the compartment and are suitably braced. When the platform 12 has reached the limit of its horizontal travel, the rollers 19 disengage from the guide rails 20, through cut away parts 21 and vertical movement of the support and the structure carrying it can now take place. A steady upward lift is obtained by the action 40 of a strong torque spring 22 (Figure 2) which acting through a peripherally grooved half-pulley attachment 23 compensates for variation 45 in the torque exerted by the spring 22 throughout the rising and falling movement of the structure, whereby a substantially constant force on 50 the structure throughout the range of movement is obtained. The spring acting through the cable 24 attached peripherally to the half-pulley 23 gives a partial rotation to a robust rocker arm 25 which by reason of a parallel linkage with a fur- 55

ther arm 26 prevents any oscillation of the platform about the pivots 27. There are, of course, two lifting arms 25 and two arms 26 one of each of which is located on the respective sides 5 of the tray platform, the arms 25 being connected by a transverse strut 25' to which the cable 24 is connected. The lifting arms 25, 26 are mounted for pivoting on two stout upstanding pillars in the form of triangular plates 28 situated one each side of the compartment 10, and 10 rigidly attached to the framework. The parallel links terminate at their forward ends in pivotal connections 27 with a robust star-shaped bracket 29, firmly attached to which are the U-shaped 15 channel members 14.

Referring now to the enlarged details, Figure 2 is an arrangement for adjusting the tension in 20 the lifting spring 22. A worm wheel 32 freely borne on the half-pulley spindle 30 has anchored to it one end of the spring 22. Rotation of the worm 31 in any conventional manually operable manner adjusts the tension between the worm wheel and the half-pulley attachment. It will be appreciated that by adjustment of the 25 spring articles of varying weights may be carried on the support, whilst it is further possible to vary the force required to cause rising and/or falling of the structure.

Figure 3 shows an arrangement for positively 30 locking the tray 12 in its uppermost position, and the arrangement is such that locking is automatic. A locking bar 33 is carried by a pin and slot arrangement 35 on the housing so as to be 35 slideable thereon. Locking detents 33A at the extremities of the bar 33 engage in apertures 34 in the bracket 29. It will be appreciated that during the final upward movement of the structure the detents 33A are displaced against the action of a return spring 36, and finally engage the apertures 40 34. Unlocking is rendered impossible until a feeler arm 37 is enabled to swing freely across a plane. Should the feeler meet with any obstructions (such as a protruding "typewriter" platen carriage) unlocking is prevented. Referring to Figures 3 and 4 it will be seen that the 45 unlocking is effected from the front of the support 12 by means of the handle 38 which is pivoted at one end and free to act within the limit of a slot 39 at the other. Thrust is transmitted 50 through an arm 40 to the bell-crank lever 41 and thence by links 42 and 43, to impart rotation to a spindle 44, which carries the feeler arm 37 and the unlocking lever 45, which on rotation contacts with the block 45A and carries the locking 55 bar 33 against the springs 36 and releases the catches 33A. The feeler 37 by reason of its excessive movement compared to that of the bell crank lever 41 will effectively prevent premature unlocking of the platform 12 if any obstruction is 60 met during its swinging movement. A return spring 46 is provided in the above arrangement.

Figure 6 shows an enlarged view of the gravity lock, (not shown in Figure 1) whereby horizontal inward movement of the platform 12 is 65 prevented until complete vertical downward movement is completed. There is provided on the underside of the U-shaped channel guide 14 a downward extending lug 48 carrying an arm 49 pivoted at 48 and notched at one end to receive 70 the edge of the back angle member of the extended platform 12. When the weighted end of the arm 49 is clear from engagement with the surface of the fixed guide rail 20, the notched end 75 will engage the rear edge of the platform angle and so effectively prevent any horizontal move-

ment except when the tray is in its lowermost position.

Figure 7 is a pictorial view showing to a reduced scale the platform in its extended position and a "typewriter" indicated in broken lines, 5 ready for use.

The device as a whole and as described, lends itself to being built as a frame or chassis capable of incorporation in furniture as a unit. The arrangement more especially of the half-pulley 10 and parallel arms is such that the device is sufficiently compact for the requirements of the office furniture trade.

What we claim is:—

1. Article transferring and positioning means 15 including a support for the article, a supporting frame, a vertically movable structure carried by said frame and slidably carrying said support for horizontal movement, a pulley rotatably mounted in said supporting frame, a pinion rotatable in 20 said supporting frame, a torsion spring of which one end is secured to said pulley and the other end is secured to said pinion, a worm engaging said pinion, a shaft carrying said worm and rotatable for effecting adjustment of the initial 25 straining of the spring, locking means to prevent vertical movement of said support except in one extreme position of horizontal movement, and locking means to prevent horizontal movement of said support except in or near one extreme 30 position of vertical movement.

2. Article transferring and positioning means 35 including a support, vertically movable means carrying said support, horizontally movable means carrying said support, locking means for restraining the movement of the support, and a feeler element co-operating in release of said locking means and depending on freedom of movement through a defined area for such co-operation.

3. Article transferring and positioning means 40 including a support for the article, the article being movable relative to the support and requiring to be within certain dimensional limits to permit operation of the device; a structure carrying said support whereby it is adapted to be withdrawn from a stowage space and thereafter raised and lowered, locking means to prevent movement of said support, a feeler element co-operating in the release of the locking means 45 and depending on freedom of movement through a definite area for such cooperation, the freedom of movement of the feeler element being interrupted in the projection of part of the article beyond the dimensional limit, and means for preventing release of said locking means except after a completed movement of the feeler element.

4. An article transferring and positioning means 50 for use with articles of which a part is liable to project beyond a dimensional limit, comprising a support for the article, a structure carrying said support whereby it is adapted to be withdrawn from a stowage space and thereafter raised and lowered; locking means to prevent downward vertical movement of said support from 55 its uppermost position, a pivoted feeler element adapted to sweep a plane into which the part might project, means for releasing said locking means, and a connection between said releasing means and said feeler element to cause the latter 60 to pivot on operation of the releasing means, and to complete its movement before release of the locking means.

5. An article transferring and positioning means 65 for use with articles of which a part is liable to 70

project beyond a dimensional limit, comprising a support for the article, a supporting frame, vertically movable means carried by said frame and slidably carrying said support for horizontal movement, balancing means adapted to exert a substantially constant force on the vertically movable means throughout its range of vertical movement, aiding its upward movement and restraining its downward movement, locking means to prevent downward vertical movement of said vertically movable means from its uppermost position, a feeler element cooperating with the locking means to permit release of the latter and requiring a predetermined movement for such operation, the said predetermined movement of the feeler element being interrupted where the article projects in part beyond the dimensional limit, and means for preventing release of said locking means except after a completed movement of the feeler element.

6. An article transferring and positioning means including a supporting platform, cooperating guide elements for compelling horizontal movement of the platform, a fixed guide bar arranged below the platform, elements depending from the platform and cooperating with the guide bar to prevent relative vertical movement of the platform during a predetermined horizontal travel, means for releasing the elements with respect to the guide bar at a predetermined point in the horizontal travel of the platform to free the platform for vertical movement, members secured to the sides of the platform, levers connected at one end to the members, fixed supports to which the levers are pivoted intermediate their ends, and means for exerting a pull on the ends of the levers remote from the members to counterbalance the weight of the article upon the platform, said means being adjustable.

7. An article transferring and positioning means including a supporting platform, cooperating guide elements for compelling horizontal movement of the platform, a fixed guide bar arranged below the platform, elements depending from the platform and cooperating with the guide bar to prevent relative vertical movement of the platform during a predetermined horizontal travel, means for releasing the elements with respect to the guide bar at a predetermined point in the horizontal travel of the platform to free the platform for vertical movement, members secured to the sides of the platform, levers connected at one end to the members, fixed supports to which the levers are pivoted intermediate their ends, means for exerting a pull on the ends of the levers remote from the members to counterbalance the weight of the article upon the platform, and means carried by the support with which the platform cooperates to engage and interlock with said members when the platform has been moved through a predetermined vertical path.

8. Article transferring and lifting means comprising a support for the article; a supporting frame; a support carrying elevator means connected to the supporting frame and movable in a vertical sense; a lever controlling the movement of said elevator means; guide means permitting horizontal movement of said support relative to the elevator means; a rotary element borne by said frame; a connection between said element and said lever; and resilient means resisting rotation of said element in one direction and ar-

ranged to exert through said element, connection and lever a movement equalizing and uniformly counter-balancing the movement exerted by said elevator means, support and article carried thereby on said lever throughout the whole range of vertical movement of said elevator.

9. Article transferring and lifting means comprising a support for the article; a supporting frame; a support carrying elevator means connected to the supporting frame and movable in a vertical sense; a lever controlling the movement of said elevator means; guide means permitting horizontal movement of said support relative to the elevator means; a pulley of varying radius rotatably borne in said frame; a flexible connection between said lever and said pulley; resilient means resisting rotation of said pulley in one direction, and arranged to exert through said pulley, connection and lever a movement equalizing and uniformly counter-balancing the movement exerted by said elevator means, support and article carried thereby on said lever throughout the whole range of vertical movement of said elevator.

10. Article transferring and lifting means as claimed in claim 8, further comprising means for adjusting the movement exerted by the resilient means through said element connection and lever.

11. Article transferring and lifting means comprising a support for the article; a supporting frame; a support carrying elevator means connected to the supporting frame and movable in a vertical sense; a lever controlling the movement of said elevator means; guide means permitting horizontal movement of said support relative to the elevator means, a rotary element borne by said frame; a connection between said element and said lever; and resilient means resisting rotation of said element in one direction and arranged to exert through said element, connection and lever a movement equalizing and uniformly counter-balancing the movement exerted by said elevator means, support and article carried thereby on said lever throughout the whole range of vertical movement of said elevator; a locking means for preventing vertical movement of said elevator means except in one extreme horizontal position of said support; and further locking means for preventing horizontal movement of said support except in or near one extreme position of vertical movement thereof.

12. Article transferring and lifting means comprising a support for the article; a supporting frame; a support carrying elevator means connected to the supporting frame and movable in a vertical sense; a lever controlling the movement of said elevator means; guide means permitting horizontal movement of said support relative to the elevator means; a rotary element borne by said frame; a connection between said element and said lever; a torsion spring resisting rotation of said element in one direction and arranged to exert through said element, connection and lever a moment equalizing and uniformly counter-balancing the movement exerted by said elevator means, support and article carried thereby on said lever throughout the whole range of vertical movement of said elevator.
